CLAIM

(21) Appl. No.: **29/314,295**

The ornamental design for the coupling housing for a mine
dewatering apparatus, as shown and described herein.

(22) Filed: **Mar. 18, 2009**

DESCRIPTION

(30) **Foreign Application Priority Data**

Sep. 22, 2008 (AU) 14550/08

FIG. 1 is a perspective view of the present invention depicting
a first end of the coupling housing for attachment to a pump of
a mine dewatering apparatus;

(51) **LOC (9) Cl.** 23-01

FIG. 2 is a perspective view of the coupling housing depicting
a second end for attachment to the engine assembly of a mine
dewatering apparatus shown in FIG. 1;

(52) **U.S. Cl.** D23/262

FIG. 3 is a side view in elevation of the mine dewatering
apparatus;

(58) **Field of Classification Search** D23/259-269;

FIG. 4 is a side view in elevation of the invention as shown in
FIG. 3, rotated 180°;

4/286-287, 295; 138/89, 91; 217/110; 220/288;

FIG. 5 is a side view in elevation of the invention as shown in
FIG. 4, rotated 90° to the right; and,

222/552, 554, 546, 563; 285/139.1, 148.18;

FIG. 6 is a plan view of the invention as shown in FIG. 4.

285/148.23, 242, 251, 256, 331, 353, 423,
